[57] CLAIM

The ornamental design for a pneumatic motor, as shown and described.

DESCRIPTION

FIG. 1 is a front view of a pneumatic motor showing our new design;

FIG. 2 is a bottom view thereof;

FIG. 3 is a back view thereof;

FIG. 4 is a top view thereof;

FIG. 5 is a right side view thereof; and,

FIG. 6 is a left side view thereof;

FIG. 7 is a front view of an alternate embodiment of the pneumatic motor shown in FIG. 1;

FIG. 8 is a bottom view thereof;

FIG. 9 is a back view thereof;

FIG. 10 is a top view thereof;

FIG. 11 is a right side view thereof; and,

FIG. 12 is a left side view thereof.

The broken line showing of elements are for illustrative purposes only and form no part of the claimed design.
